PUMP

Frank R. Abbott, San Diego, Calif., assignor to
 General Electric X-Ray Corporation, Chicago,
 Ill., a corporation of New York

Application April 8, 1942, Serial No. 438,151

9 Claims. (Cl. 230—101)

My invention relates in general to pumping and has more particular reference to pumping for the production of extremely low pressure, the invention pertaining especially to the production of vacuum conditions by diffusion pumping.

An important object of the invention is to provide an improved diffusion pump characterized by the absence of activated charcoal and liquid air traps heretofore considered essential in diffusion pumps, thus eliminating the necessity of frequent maintenance operations required to keep the trap in serviceable condition.

Another important object is to provide suitable apparatus for vaporizing the pumping medium, directing the vapor as a pumping jet, and condensing the vapor and recirculating the condensed medium for repetition of the pumping cycle, while maintaining the pumping medium at the necessary temperatures required at the various stages in the pumping cycle.

Another important object is to provide an improved jet structure for use in a diffusion pump; a further object being to utilize an annular jet arrangement; a still further object being to utilize lava or similar refractory material in forming a jet nozzle for a diffusion pump.

Another important object is to provide a diffusion pump wherein the pumping medium is vaporized by an electric arc maintained between a suitable anode and pumping medium in molten condition as a cathode; a further object being to utilize a tungsten anode for the establishment of the heating arc; a further important object being to utilize aluminum oxide or other inert material as a crucible or container for supporting the liquid pumping medium in position to form an arcing cathode.

Another important object is to provide improved means for adjusting the arcing anode in the pump; a further object being to provide means for maintaining the anode at a desired temperature during the operation of the pump.

Another important object is to provide means for sealing the pump against the escape of pressure at the place where the anode adjusting means extends outwardly of the pump casing.

Another important object is to provide a diffusion pump having a heating chamber for the evaporation of a heating medium, including means preferably forming an evacuated jacket around said heating chamber in order to minimize heat loss outwardly of said chamber, thereby improving the efficiency of the pump.

Another important object is to provide a diffusion pump having means for evaporating the pumping medium by resistance heating; a further object being to utilize a column of molten pumping medium as the resistance heater and to provide means for passing an electrical cur-

rent of suitable magnitude through said column for the purpose of vaporizing the medium.

Another important object is to form the casing of the pumping mechanism in separable sections, including a heater section and a nozzle section, and to utilize a soft iron gasket, preferably copper plated, as a seal between the heater and jet sections of the pump housing.

Another important object is to form the heater section as a casing of steel, preferably a seamless steel tube containing a liner for defining a heating chamber for the pumping medium, opening to a jet nozzle located in a jet chamber forming part of the jet housing, the jet chamber communicating with a pumping chamber and also with a condensation space formed in the heater section of the pump housing; a further important object being to provide a pump comprising parts of simple form readily produced and easily assembled.

20 Another important object is to provide a pump structure which may be used as a pump operated by a resistance heater or by an arc heater merely by assembling the appropriate heater section in the pump structure.

25 These and numerous other important objects, advantages, and inherent functions of the invention will be fully understood from the following description, which, taken in connection with the accompanying drawing, discloses preferred embodiments of the invention.

Referring to the drawing:

Figure 1 is a sectional view taken through a diffusion pump operated by an arc; and

35 Figure 2 is a sectional view taken through the lower portions of a diffusion pump embodying a resistance heater.

To illustrate the invention, I have shown on the drawing diffusion pumps, each comprising a housing forming a vaporizing chamber 11 communicating upwardly with a jet nozzle 13 preferably designed to project annular jets downwardly into an annular condensing chamber 15 which surrounds the vaporizing chamber 11.

40 The condensing chamber 15 comprises communicating cavities formed, respectively, in the end of a section 17 comprising the heating section of the pump housing and in a head 19 comprising the jet section of the housing, the jet nozzle 13 being located within the upper portions of the head 19 remote from the section 17. The section 17 may comprise a tube having a flanged open end adapted to be secured, as by bolts, to the head 19. A sealing gasket 18 preferably of

55 soft iron coated with copper may be used at the joint to seal the same, soft iron being particularly well suited to maintain a tight joint between the head 19 and the section 17 through the range of operating temperature involved.

60 The head 19 preferably comprises a block of

steel having therein the cavity forming the upper portion of the condensing chamber 15, said cavity communicating upwardly of the jet nozzle 13 with a pumping chamber 21 through an opening 23 forming a continuation of the chamber 15. The walls of the pumping chamber 21 may be formed in any suitable or preferred fashion, as by means of a glass sleeve 25, the opposite annular edges of which form glass-to-metal seals 27 with an annular preferably steel disk or washer 29 formed with a central opening. The edges of the central opening of one of the disks 29 are brazed or otherwise sealingly secured, as at 31, upon the upper side of the head 19 around the opening 23, the central opening of the other disk being sealingly secured in like fashion to the end of a pumping head 35 comprising, in the illustrated embodiment, a cup-like element having a cavity 37 in open communication with the pumping chamber 21. The pumping head 35 is fitted with a fine vacuum connection comprising a nipple 39 which communicates with the cavity 37 through a side wall of the head 35, the nipple 39 being connectible with any hollow envelope or casing enclosing a space to be evacuated.

The bottom of the cup-like element 35 is formed with an opening 41 through which extends a tubular anode support 43, the space between the member 43 and the edges defining the opening 41 being sealed by means of a metallic bellows 45, one end of which is sealed to the head around the opening 41 and the other end of which is sealed to an annular flange 47 which, in turn, is sealed on the member 43. The bellows 45 is enclosed within and protected by a preferably steel sleeve 49, one end of which is fastened, as by set screws, to the head 35, and the other end of which supports a collar 51 which is internally threaded, as at 53, for the reception of a gland 55 which carries the tubular member 43 and which is formed with a manually operable head 57 to facilitate the turning of the gland 55 in the collar 51 in order to raise or lower the member 43.

The end of the tubular member 43 extends within the pumping chamber 21 and carries, sealed thereto, a preferably steel block 59 forming a mounting head for an anode. This anode preferably comprises a slender rod 60 of molybdenum, which is secured at one end as by threading the same in the mounting head 59, the rod at its opposite end carrying a tip 61 of tungsten or carbon. The rod 60 is preferably provided with a thin sheath 63 of inert refractory material, such as aluminum-oxide, the sheath extending throughout the rod from the mounting head 59 to the tip 61 which is exposed.

The exposed end or tip 61 of the anode extends within the heating chamber 11, which comprises a cavity for the reception of a suitable pumping medium 65, which forms a molten pool in the bottom of the chamber 11 in position to form a cathode for co-operation with the tip of the anode. By applying a suitable electrical potential between the anode and the pool of molten pumping medium, an arc may be struck between the anode and the cathode for the purpose of vaporizing the pumping medium in the chamber 11.

As shown in Figure 1, the chamber 11 is defined within the casing portion 17 by a block 67 of inert refractory material, such as aluminum-oxide. This block of material 67 is formed to fit snugly within the walls defining the housing

portion 17, which preferably comprises a steel tube having an open end adapted to be mountably secured to the head 19, as by means of the fastening bolts 69, the opposite end of the tube 17 being closed by means of a steel disk or plate 71 welded or otherwise sealingly secured to the lower end of the tube 17. The block of refractory material 67 is fitted snugly within the tube 17 and rests at its lower end upon the plate 71, thus entirely filling the lower portions of the tube. The block 67 has a central cavity forming the chamber 11 and is cut away as at 73 to provide a cylindrical neck 75 within the upper portions of the casing section 17, said neck extending into the cavity forming the chamber 15 in the head 19, thereby defining the upper portions of the vaporizing chamber within the condensing chamber 15, inwardly of the cylindrical neck 75.

20 The jet nozzle 13 comprises an annular rim 77 mounted upon the upper extremity of the neck 75, said rim preferably comprising lava or equivalent refractory material and being sealed, as by means of suitable cement, upon the sleeve-like neck 75. The rim 77 is preferably formed with upstanding fingers 79 formed at intervals around the rim for the support of an annular skirt-like nozzle element 81, which overlies the rim 77 and is supported in place by the fingers 79 in position forming, with the rim 77, an annular jet nozzle through which vapor generated in the chamber 11 by the heating of the pumping medium 65 may be projected downwardly into the condensing chamber 15. The annular skirt-like nozzle member 81 preferably comprises lava or other equivalent refractory material and is formed with a central opening through which the rod 60 extends, said rod being axially movable through said opening. Preferably, a helical spring 83 encircles the rod 60 between the mounting head 59 and the central portions of the nozzle member 81 to yieldingly urge the same downwardly into seated position upon the supporting fingers 79.

I prefer also to enclose the mounting head 59 and the portions of the rod 60 and of the member 43 which extend in the chamber 21 between the head 35 and the nozzle element 81. This is accomplished by means of a sleeve 85 preferably formed of lava, which is annularly sealed at one end to the nozzle element 81 and which extends at its other end to the bottom of the cup-shaped head 35 forming the cavity 37.

The lower end of the block 67 is preferably formed with an axial channel 87 for the snug reception of a pin 89, which is fastened at one end in the disk 71 and which extends at its other end within the lower portions of the chamber 11 in contact with the pool of pumping material 65.

60 The pumping medium vaporized in the chamber 11 is expelled from the upper end of the chamber in the form of an annular jet through the nozzle means and passes downwardly in the condensing chamber 15. The action of the jet 65 produces low pressure conditions in the chamber 21 and in the vessel connected to the nipple 39. The vaporized pumping medium projected into the chamber 15 condenses therein to a molten condition and escapes thence through a return circuit to the pool 65 at the lower end of the heating chamber 11. To this end, I provide a return conduit 91 connecting through the wall of the housing portion 17 with the lower portions of the condensing chamber 15, the conduit means 91, at its other end, being connected,

through an opening in the casing portion 17 and through a duct 93 in the block 67, with the lower end of the heating chamber 11. The condensation chamber 15 into which the pumping chamber 21 evacuates is connected with suitable exhaust discharge means, such as a mechanical exhaust pump, which may be connected with the chamber 15 through the upper portions of the conduit 91. To this end, the conduit 91, at its upper end, is provided with a take-off pipe 95 adapted for connection with an exhaust pump.

The heating arc between the anode 61 and the pool of pumping medium 65 operating as a cathode may be maintained in operation by electrical potential applied between the casing portion 17 which is electrically connected with the cathode pool by the pin 89 and the collar 51 which is electrically connected with the anode through the mounting sleeve 43, the casing portions being electrically insulated by the glass sleeve 25. In order to maintain the pumping chamber 21 at a desired low temperature, the anode tube 43 may be extended upwardly of the adjusting head 57 and provided with an inlet 97 through which a cooling liquid may be introduced into the sleeve 43. Within the sleeve 43 I may mount a tube 99, one end of which opens outwardly of the projecting end of the tube 43, and the other end of which opens within said tube adjacent the head 59 so that the cooling fluid introduced to the tube 43 at its projecting end will pass to the end thereof within the chamber 21, thus conducting heat from the end of the anode rod 60 which extends in said pumping chamber to thereby maintain said chamber at a desired temperature of the order of 400° C., the lava sleeve 85 serving to prevent the escape of heat from the anode into the surrounding portions of the pumping chamber.

The arrangement illustrated in Figure 2 of the drawing embodies a modified construction of the parts forming the vaporizing chamber 11, in order to provide for the vaporization of the pumping medium by resistance heating or by a combination of resistance and arc heating. As shown in Figure 2, the vaporizing chamber 11 comprises a steel tube 101 carrying the annular nozzle member 77 at its upper end. The lower end of the tube 101 is closed by a plug 103 sealed in said tube and carrying a downwardly extending pipe 105 of limited diameter which extends through the plug 103 and communicates with the vaporizing chamber 11. The casing 17 also is extended downwardly below the disk 11 by means of an extension tube 107, the upper end of which is sealed in an opening formed in the disk 11, the other end of the tube 107 being closed by a disk 109. The tube 105 extends within the extension 107 and opens, as at 111, adjacent the disk 109. The communicating steel tubes 101 and 105 are jacketed by means of a tube 113 enclosing the tube 105, a sleeve 115 enclosing the lower portions of the tube 101, and a tube 117 enclosing the upper portions of the tube 101, the tubes 113 and 117 being sealed in open communication with the opposite ends of the sleeve 115 by means of collars 119 and 121, the end of the tube 113 remote from the sleeve 115 being sealed on the tube 105 near its end 111 by means of a sealing collar 123, and the tube 117 being sealed to the nozzle carrying end of the tube 101, thus forming a sealed jacket around the connecting tubes 101 and 105, which jacket comprises an evacuated space 125.

The sleeve 115 fits snugly within the casing

portion 17, and the collar 119 defines the bottom of the annular condensing chamber 15 within said casing portion 17 which is formed, as at 127, to provide for the return of pumping medium 5 condensed in the chamber 15, through the casing extension 107, to the lower open end 111 of the tube 105. The casing 17 also is provided with an exhaust connection 129 which communicates the lower portions of the condensing chamber 15 with a suitable exhaust device such as a mechanical pump.

As in the pump structure shown in Figure 1, the pumping medium forms a pool 65 in the lower portions of the vaporizing chamber 11 within the tube 101, the pumping medium being vaporized by the application of electrical potential between the casing portions 17 or 107 and the rod 60, the end of which may be spaced slightly above the liquid level of the pool 65 in order to cause arcing for heating purposes, or a tip of the rod 60 may be immersed in the molten pool 65. In either event, resistance heating will be accomplished by the passage of electrical current between the rod 60 and the disk 109 through the column of the molten material in the tube 105 in order to generate vapor in the chamber 11 for projection through the nozzle means 13. The provision of an evacuated jacket space 125 around the heating chamber prevents heat loss outwardly from the chamber and thereby materially improves the efficiency of the pump.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the forms herein disclosed being preferred embodiments for the purpose of illustrating the invention.

The invention is hereby claimed as follows:

1. A diffusion pump comprising means forming an evaporation chamber, a condensing chamber, a pumping chamber connected with the condensing chamber through an orifice, and a vapor jet nozzle, comprising a refractory material such as lava, connected with the evaporation chamber and opening into said condensing chamber adjacent said orifice, said nozzle facing in a direction away from said orifice whereby to reduce pressure in said pumping chamber when said nozzle is in operation.

2. A diffusion pump comprising means forming an evaporation chamber, a condensing chamber, a pumping chamber connected with the condensing chamber through an orifice, and a vapor jet nozzle connected with the evaporation chamber and opening into said condensing chamber adjacent said orifice, said nozzle facing in a direction away from said orifice, said evaporation chamber comprising a member having a sleeve-like portion extending in the condensing chamber and means forming a heat insulating jacket around said evaporation chamber and extending between it and said condensing chamber.

3. A diffusion pump comprising means forming an evaporation chamber, a condensing chamber, a pumping chamber connected with the condensing chamber through an orifice, and a vapor jet nozzle connected with the evaporation chamber and opening into said condensing chamber adjacent said orifice, said nozzle facing in a direction away from said orifice, said chambers being formed in a housing comprising a pair of

spaced metal heads respectively forming a condensing head and a pumping head, the condensing chamber being formed in the condensing head and said evaporation chamber being defined by partition means extending within the condensing chamber, the pumping chamber comprising wall means on the pumping head, and means insulating the heads the one from the other.

4. A diffusion pump comprising means forming an evaporation chamber, a condensing chamber, a pumping chamber connected with the condensing chamber through an orifice, and a vapor jet nozzle connected with the evaporation chamber and opening into said condensing chamber, adjacent said orifice, said nozzle facing in a direction away from said orifice, said chambers being formed in a housing comprising a pair of spaced metal heads respectively forming a condensing head and a pumping head, the condensing chamber being formed in the condensing head and said evaporation chamber being defined by partition means extending within the condensing chamber, the pumping chamber comprising wall means on the pumping head, and means insulating the heads the one from the other and comprising a tubular glass wall sealed at its opposite ends to the pumping and condensing heads and defining the condensing chamber on the pumping head.

5. A diffusion pump comprising means forming an evaporation chamber, a condensing chamber, a pumping chamber connected with the condensing chamber through an orifice, and a vapor jet nozzle connected with the evaporation chamber and opening into said condensing chamber adjacent said orifice, said nozzle facing in a direction away from said orifice, said chambers being formed in a housing comprising a pair of spaced metal heads respectively forming a condensing head and a pumping head, the condensing chamber being formed in the condensing head and said evaporation chamber being defined by partition means extending within the condensing chamber, the pumping chamber comprising wall means on the pumping head, means insulating the heads the one from the other, and electrode means on said pumping head and extending through said pumping chamber and into said evaporation chamber in position to heat an evaporable pumping medium in the evaporation chamber.

6. A diffusion pump comprising means forming an evaporation chamber, a condensing chamber, a pumping chamber connected with the condensing chamber through an orifice, and a vapor jet nozzle connected with the evaporation chamber and opening into said condensing chamber adjacent said orifice, said nozzle facing in a direction away from said orifice, said chambers being formed in a housing comprising a pair of spaced metal heads respectively forming a condensing head and a pumping head, the condensing chamber being formed in the condensing head and said evaporation chamber being defined by partition means extending within the condensing chamber, the pumping chamber comprising wall means on the pumping head, means insulating the heads the one from the other, electrode means on said pumping head and extending through said pumping chamber and into said evaporation chamber in position to heat an evaporable pumping medium in the evaporation chamber, and means manually operable outwardly of the pumping head for adjusting the electrode means longitudinally of said pumping head.

7. A diffusion pump comprising means forming an evaporation chamber, a condensing chamber, a pumping chamber connected with the condensing chamber through an orifice, and a vapor jet nozzle connected with the evaporation chamber and opening into said condensing chamber adjacent said orifice, said nozzle facing in a direction away from said orifice, said chambers being formed in a housing comprising a pair of spaced metal heads respectively forming a condensing head and a pumping head, the condensing chamber being formed in the condensing head and said evaporation chamber being defined by partition means extending within the condensing chamber, the pumping chamber comprising wall means on the pumping head, means insulating the heads the one from the other, electrode means on said pumping head and extending through said pumping chamber and into said evaporation chamber in position to heat an evaporable pumping medium in the evaporation chamber, means manually operable outwardly of the pumping head for adjusting the electrode means longitudinally of said pumping head, and means for hermetically sealing the electrode means where it penetrates outwardly of the pumping head.

8. A diffusion pump comprising means forming an evaporation chamber, a condensing chamber, a pumping chamber connected with the condensing chamber through an orifice, and a vapor jet nozzle connected with the evaporation chamber and opening into said condensing chamber adjacent said orifice, said nozzle facing in a direction away from said orifice, said chambers being formed in a housing comprising a pair of spaced metal heads respectively forming a condensing head and a pumping head, the condensing chamber being formed in the condensing head and said evaporation chamber being defined by partition means extending within the condensing chamber, the pumping chamber comprising wall means on the pumping head, means insulating the heads the one from the other, electrode means on said pumping head and extending through said pumping chamber and into said evaporation chamber in position to heat an evaporable pumping medium in the evaporation chamber, and means to circulate a cooling fluid in said electrode means within said pumping chamber.

9. A diffusion pump comprising means forming an evaporation chamber, a condensing chamber, a pumping chamber connected with the condensing chamber through an orifice, and a vapor jet nozzle connected with the evaporation chamber and opening into said condensing chamber adjacent said orifice, said nozzle facing in a direction away from said orifice, said chambers being formed in a housing comprising a pair of spaced metal heads respectively forming a condensing head and a pumping head, the condensing chamber being formed in the condensing head and said evaporation chamber being defined by partition means extending within the condensing chamber, the pumping chamber comprising wall means on the pumping head, means insulating the heads the one from the other, electrode means on said pumping head and extending through said pumping chamber and into said evaporation chamber in position to heat an evaporable pumping medium in the evaporation chamber, and a heat insulating sleeve encircling the electrode means in the pumping chamber.
